(57) **CLAIM**

The ornamental design for a shaving razor, as shown and described.

DESCRIPTION

FIG. 1 is a left front perspective view of a shaving razor in a face shaving configuration;

FIG. 2 is a right bottom perspective view of the shaving razor of FIG. 1;

FIG. 3 is a top plan view of the shaving razor of FIG. 1;

FIG. 4 is a left side elevational view of the shaving razor of FIG. 1;

FIG. 5 is a right side elevational view of the shaving razor of FIG. 1;

FIG. 6 is a bottom plan view of the shaving razor of FIG. 1;

FIG. 7 is a front elevational view of the shaving razor of FIG. 1;

FIG. 8 is a rear elevational view of the shaving razor of FIG. 1;

FIG. 9 is a left front perspective view of the shaving razor in a head shaving configuration;

FIG. 10 is a left bottom perspective view of the shaving razor of FIG. 9;

FIG. 11 is a top plan view of the shaving razor of FIG. 9;

FIG. 12 is a left side elevational view of the shaving razor of FIG. 9;

FIG. 13 is a right side elevational view of the shaving razor of FIG. 9;

FIG. 14 is a bottom plan view of the shaving razor of FIG. 9;

FIG. 15 is a front elevational view of the shaving razor of FIG. 9; and,

FIG. 16 is a rear elevational view of the shaving razor of FIG. 9.
